TUBE-SEVERING MECHANISM

Anthony F. Cibs, Cleveland Heights, Ohio, assignor to Chase Brass & Copper Co. Incorporated, Waterbury, Conn., a corporation

Application August 25, 1942, Serial No. 456,017

1 Claim. (Cl. 164—47)

1

The present invention relates to improvements in cutting mechanisms and relates more particularly to improvements in mechanisms for transversely severing tubes into desired lengths. The present invention, while not so limited, is especially well suited for producing rotating-bands for artillery projectiles from copper or the like.

One of the objects of the present invention is to provide a superior tube-severing mechanism which will effectively transversely sever a tube without materially distorting the same.

Another object of the present invention is to provide a mechanism of the character referred to which will effectively sever tubes into desired lengths without creating appreciable chips or other waste material.

A further object of the present invention is to provide a superior tube-severing mechanism which will transversely sever a tube so cleanly as to minimize the need for a subsequent operation.

Still another object of the present invention is to provide a superior tube-severing mechanism which will rapidly and effectively transversely sever a tube without creating appreciable waste material and without material distortion of the product.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken view partly in side elevation and partly in vertical central-longitudinal section of one form of tube-severing mechanism constructed in accordance with the present invention, and with the parts in the positions which they assume immediately prior to the tube-cutting operation;

Fig. 2 is a view in vertical central-longitudinal section of the mechanism at the right of Fig. 1 but on a larger scale and with the parts in the same positions as in Fig. 1;

Fig. 3 is a view corresponding to Fig. 2 but showing the parts in the positions which they assume immediately following the completion of the tube-severing operation;

Fig. 4 is a view partly in plan but mainly a horizontal sectional view taken on the line 4—4 of Fig. 2;

Fig. 5 is a transverse sectional view taken on the line 5—5 of Fig. 2;

2

Fig. 6 is a perspective view of the movable cutter-holder together with its tubular outer cutter;

Fig. 7 is a perspective view of the movable inner-cutter looking mainly toward the outer end thereof;

Fig. 8 is a perspective view of the stationary outer-cutter, detached;

Fig. 9 is a broken perspective view of the inner 10 end of the stationary inner-cutter, detached;

Fig. 10 is a perspective view of the movable inner-cutter, detached;

Fig. 11 is a perspective view of the movable outer-cutter, detached;

15 Fig. 12 is a broken perspective view of a length of tube;

Fig. 13 is a perspective view of a ring cut from a tube by the mechanism of the preceding figures; and

20 Fig. 14 is a perspective view of the stripping-plunger, detached.

The particular tube-severing mechanism shown in the accompanying drawings for purposes of illustrating one form of the present invention, 25 includes a stationary tubular outer-cutter 15, a stationary rod-like inner-cutter 16, a movable tubular outer-cutter 17 and a movable rod-like inner-cutter 18.

The stationary outer-cutter 15 is preferably 30 formed of high-grade steel and is of tubular form with its interior and exterior both cylindrically contoured. The said stationary outer-cutter 15 has the entire annular edge at the junction of its inner perimeter and its inner face 35 sharpened, though it is substantially only the lower semicircle which acts as a cutting-edge 19 having an extent substantially corresponding to the portion embraced by the bracket 20 in Fig. 8. While, as just noted, it is only the lower half

40 of the edge of the inner portion of the stationary outer-cutter 15 which functions as a cutting-edge, nevertheless, for simplicity and economy of construction, the said outer-cutter is preferably in the form of a tube, as shown, and its interior is sized and proportioned to have a snug sliding fit around the periphery of a tube 21 constituting the blank from the inner end of which is to be successively cut short lengths to provide rings such as the ring 22 shown in Figs. 3 and 13.

45 The rod-like inner-cutter 16 is designated as the stationary inner-cutter for the reason that it, like the outer-cutter 15, has no lateral movement during the cutting operation, though it is movable axially for purposes of installing a fresh tube 50 thereon, such as 21, as will more fully herein-

after appear. The said rod-like stationary inner-cutter 16 has its outer periphery snugly engaging with a sliding fit the inner periphery of the tube 21. Furthermore and as is shown especially well in Fig. 2, the inner end of the stationary inner-cutter 16 is arranged flush with the inner end of the stationary outer-cutter 15. The forward upper corner of the inner-cutter 16 constitutes a transverse cutting-edge 23 which latter has an extent of substantially a semicircle as defined within substantially the limits of the bracket 24 indicated in Fig. 9. The tubular stationary outer-cutter 15 is rigidly mounted in a cutter-holder or block 25 supported on a base-plate 26 and connected to a framework 27 of any suitable type.

As will be noted by reference to Fig. 1, the stationary inner-cutter 16 is relatively quite long and has its outer end releasably mounted in an anchoring-head 28 so as to be held against both lateral and axial movement under normal operating conditions. The said anchoring-head 28 is, in turn, coupled in any suitable manner to the outer end of the framework 27, which latter also supports a tube-feeding head 29 (Fig. 1) having the mandrel-like inner-cutter 16 extended therethrough and having capacity for sliding movement in a direction parallel with the longitudinal axis of the cutter 16. The tube-feeding head 29 is provided with a pivotal dog 30 having a nose 31 adapted to be released from and entered into the gaps in a tube-feeding chain 32 of conventional roller-chain type.

Returning now to the movable outer-cutter 17, it will be noted that the said cutter is rigidly mounted in a movable cutter-holder or block 33 having its inner or left face in sliding engagement with the inner or right face of the stationary cutter-holder 25 before referred to, as is especially well shown in Figs. 1 to 4 inclusive. At each of its respective opposite sides, the right or outer face of the cutter-holder 33 has sliding engagement with and is guided by two laterally-spaced-apart spacing-blocks 34—34 suitably secured to the framework 27. The respective outer or right edges of the spacing-blocks 34—34 (Fig. 4) are seated against the left face of a block-like crosshead 35 also rigidly secured to the framework 27. The said crosshead 35 is formed in its inner or left face with a vertical groove 36 in which is mounted a cam-plate 37 having in its left face an advance-dwell 38 extending perpendicularly with respect to the axis of the tube 21 and a similarly-extending retirement-dwell 39 displaced to the right with respect to the advance-dwell 38 and connected thereto by an inclined surface 40. The cam-plate 37 is adjustable in the groove 36 of the crosshead 35 by means of a plurality of horizontal set-screws 41 mounted in the outer portion of the said crosshead.

The movable inner-cutter 18 before referred to is provided at its outer or right end with a cam-head 42 having a portion extending into and vertically sliding in the groove 36 in the crosshead 35 and shaped for sliding engagement with the surfaces 38, 39 and 40 of the cam-plate 37 located in the said groove. The cylindrically-contoured body-portion of the said movable inner-cutter 18 corresponds in size to the normally-stationary inner-cutter 16 and hence corresponds in size to the interior diameter of the tube 21. The inner lower corner of the inner-cutter 18 constitutes a cutting-edge 43 having a transverse

extent substantially corresponding to the portion embraced by the bracket 44 in Fig. 10.

The inner portion of the movable inner-cutter 18 is surrounded by an axially-adjustable gauge-sleeve 45 having its inner edge spaced outwardly from the inner face of the cutter 18 a distance corresponding to the desired width of the ring 22 to be produced. The said gauge-sleeve 45 is axially adjustable by means of an adjusting-nut 46 threaded into the outer portion of the movable cutter-holder or block 33. Bearing against the outer face of the adjusting-nut 46 is the inner end of a helical cutter-retiring spring 47 which has its outer end bearing against the inner face of the cam-head 42 of the inner-cutter 18. As thus arranged, the cutter-retiring spring 47 serves to yieldingly urge the entire movable inner-cutter 18 axially outwardly away from the stationary inner-cutter 16.

The movable cutter-cutter 17 has an internal diameter corresponding to the internal diameter of the stationary outer-cutter 15 with respect to which it is in end-to-end relationship and receives in its interior the gauge-sleeve 45, which latter substantially corresponds in thickness to the thickness of the tube 21. The corner formed at the junction of the upper portion of the inner face of the cutter 17 and the upper portion of its inner perimeter constitutes a cutting-edge 48 of a lateral extent substantially corresponding to that embraced by the bracket 49 in Fig. 11. The lower inner portion of the movable outer-cutter 17 is cut away to a depth slightly exceeding the width of the ring 22 to provide a clearance-notch 50 forming a vertical continuation of a clearance-notch 51 formed in the inner face of the vertically-movable cutter-holder 33, all for purposes as will hereinafter appear.

The vertically-movable cutter-holder 33 before described is yieldingly urged upwardly to normally maintain its cutters 17 and 18 in axial alignment with the stationary cutters 15 and 16, by means of a plurality of vertically-reciprocating plungers 52 extending upwardly through and guided in the base-plate 26. The lower ends of the plungers 52 are mounted in a plunger-plate 53 located beneath the base-plate 26 and sliding upon a vertical stud 54 anchored at its upper end in the said base-plate 26. Encircling the stud 54 at a point below the plunger-plate 53 is a helical return-spring 55 thrusting at its upper end against the underside of the plunger-plate 53 and resting at its lower end upon a disk-like spring-seat 56 secured to the lower end of the stud 54 by means of one or more nuts 57, as is shown in Fig. 1.

As thus constructed and arranged, the return-spring 55 and associated parts serve to normally maintain the movable cutter-holder 33 in its uppermost position, in which the outer and inner movable-cutters 17 and 18 are in precise axial alignment with the normally-stationary outer- and inner-cutters 15 and 16. The upward movement of the cutter-holder 33, and hence of the parts carried thereby, is limited by the engagement of upper portions of the said holder with adjacent portions of the framework 27.

Below its cutters 15 and 16, the stationary cutter-holder or block 25 is formed in its inner face with a cylindrically-contoured recess 58, from the end wall of which leads an eccentrically-located cylindrically-contoured recess 59 of relatively-smaller diameter than the recess 58. Leading to the left from the end wall of the recess 59 to the left side of the cutter-holder 25,

is a passage 60 smaller in diameter than the recess 59 and arranged concentrically therewith.

In the relatively-large-dia-metered recess 58 there is located the cylindrically-contoured head 61 of a reciprocating stripping-plunger 62. The said head 61 has a downwardly-and-inwardly-sloping inner face and has a diameter only slightly less than the internal diameter of the ring 22 before referred to. The stripping-plunger 62 also includes a cylindrically-contoured shank 63 reciprocating in the recess 59 and extending outwardly from the head 61 in eccentric relationship thereto. The stripping-plunger 62 also includes a relatively-small-dia-metered stem 64 rigid with and extending outwardly from the shank 63 through the passage 60 in the cutter-holder 25. As shown, the outer end of the stem 64 which projects beyond the left face of the stationary cutter-holder 25, is provided with one or more adjustable stop-nuts 65 which serve to limit the movement of the plunger 62 in a direction from left to right. Encircling the stem 64 and thrusting at its respective opposite ends against the shank 63 and the end wall of the recess 59, is a helical spring 66 which exerts a constant effort to move the stripping-plunger 62 from left to right.

Immediately below the outer tip of the stripping-plunger 62 and below the clearance-notches 50 and 51 respectively formed in the outer-cutter 17 and the cutter-holder 33, is a discharge-passage 67 extending vertically through the base-plate 26 and designed and adapted to have successive rings like 22 pass downwardly therethrough as the same are cut off from a tube such as 21.

The downward or cutting-stroke of the movable cutter-holder 33 may be effected in any approved manner but for purposes of illustration of one form of the application of the necessary power, there is shown in Figs. 1, 2 and 3, the ram 68 which may form a feature of a power press and which is adapted to impinge against the upper surface of the movable cutter-holder 33.

To make clear the operation of the mechanism shown in the accompanying drawings and above described, let it be assumed that the parts occupy the positions in which they are shown in Figs. 1 and 2, in which it will be noted that the end of the tube 21 is abutted against the adjacent end of the gauge-sleeve 45. It is also to be noted that the movable inner-cutter 18 is at the limit of its movement to the left and therefore its cutting-edge 43 is in transverse alignment with the respective cutting-edges of the stationary inner-cutter 16, stationary outer-cutter 15 and movable outer-cutter 17.

If now, the ram 68 is caused to descend, it will force the movable cutter-holder 33 and the parts carried thereby downwardly from the positions in which they are shown in Figs. 1 and 2, into the positions in which they are shown in Fig. 3. The movement referred to will cause the cutting-edge 48 of the movable outer-cutter 17 to coact with the cutting-edge 23 of the stationary inner-cutter 16 to thereby sever the upper half of the tube 21, indicated by the bracket 69 in Fig. 12. Simultaneously also and during the severing action just referred to, the substantially semicircular transverse cutting-edge 43 of the movable inner-cutter 18 will coact with the substantially-semicircular transverse cutting-edge 19 of the stationary outer-cutter 15 to sever the lower half of the tube 21, indicated by the bracket 70 in Fig. 12.

The severing just above referred to will result in the creation of a ring such as 22, and the continued downward movement of the parts will transport the said ring and the other parts referred to downwardly into the positions in which they are shown in Fig. 3. It is here to be noted that immediately following the completion of the severance of the ring 22 from the tube 21, the movable inner-cutter 18 is axially retired from left to right by the cutter-retiring spring 47. This movement is made possible by the sliding of the cam-head 42 of the said cutter 18 down the incline 40 and onto the retirement-dwell 39 of the cam-plate 37.

In reaching the position in which it is shown in Fig. 3, the severed ring 22 will have engaged with the sloping inner face of the stripping-plunger 62 and will have forced the same to retire to the left against the tension of its spring 66. When, however, the ring 22 reaches a position in axial alignment with the head 61 of the stripping-plunger 62, the said stripping-plunger will move to the right under the urge of its spring 66 and enter the outer end of its head 61 into the interior of the ring 22, as is shown in Fig. 3. The ram 68 will now be caused to retire upwardly, thereby permitting the return-spring 55 to assert itself and act through the associated parts to return the movable cutter-holder 33 and the parts carried thereby back into the positions in which they are shown in Figs. 1 and 2. During this upward travel of the movable cutter-holder 33 and associated parts, the just-severed ring 22 will be restrained against upward movement by the stripping-plunger 62, and when the parts of the mechanism ultimately reach the positions in which they are shown in Figs. 1 and 2, the previously-restrained ring 22 will be free to drop off of the head 61 of the stripping-plunger 62 and pass downwardly through the discharge-passage 67 in the base-plate 26 and thence into a suitable receptacle.

As the parts move from the positions in which they are shown in Fig. 3 back to the positions in which they are shown in Figs. 1 and 2, the cam-head 42 of the movable inner-cutter 18 will ride up the slope 40 and onto the advance-dwell 38 of the cam-plate 37, thereby moving the cutter 18 axially to the left and back into its cutting position.

Following the restoration of the parts to the positions in which they are shown in Figs. 1 and 2, the tube 21 may be again advanced until its fresh-cut end is again seated against the adjacent end of the tubular gauge-sleeve 45, preparatory to another cycle of operation of the mechanism. This feeding of the tube 21 may be effected in any suitable manner by advancing the tube-feeding chain 32 to the right, thereby causing the tube-feeding head 29 to thrust against the outer end of the tube 21.

By means of the present invention, a tube of copper or other material may be severed into desired lengths without the creation of appreciable chips or other waste material, and with but a minimum, if any, distortion of the tube.

The invention may be carried out in other specific ways than those herein set forth without departing from the spirit and essential characteristics of the invention, and the present embodiment is, therefore, to be considered in all respects as illustrative and not restrictive, and all changes coming within the meaning and equivalency range of the appended claim are intended to be embraced therein.

I claim:

A tube-cutting mechanism, including in combination: a first cutter-holder; a first outer-cutter having a transverse cutting-edge at its inner end substantially conforming in size and shape to the outer perimeter of a first half of a tube to be cut and carried by the said first cutter-holder; a first inner-cutter located within the said first outer-cutter and having a transverse cutting-edge located at its inner end in substantial transverse alignment with the cutting-edge of the said first outer-cutter and substantially conforming in size and shape to the interior perimeter of the second half of the tube to be cut; a second cutter-holder movable in a direction transverse to the axes of the said first outer-cutter and the said first inner-cutter; a second outer-cutter carried by the said second cutter-holder in end-to-end relationship with the said first outer-cutter and having a transverse cutting-edge in substantial transverse alignment with the respective cutting-edges of the before-mentioned cutters and substantially conforming in size and shape to the exterior perimeter of the second half of the tube to be cut; a second inner-cutter disposed within the said second outer-cutter in end-to-end relationship with respect to the said first inner-cutter and having a transverse cutting-edge at its inner

end located in substantial transverse alignment with the inner ends of the before-mentioned cutters and substantially conforming in size and shape to the inner perimeter of the first half of the tube to be cut, the said second inner-cutter being axially movable toward and away from the said first inner-cutter; the said second outer-cutter being cut away or relieved at its inner end opposite its transverse cutting-edge to provide a clearance-passage for the substantial radial discharge of a severed portion of the tube; a spring-pressed stripping-member secured to the said first cutter-holder and located outwardly of and in line with the clearance-passage in the said second outer-cutter; means for moving the said second cutter-holder and the second outer-cutter and inner cutter carried thereby in a direction transverse to the axis of the tube to be cut to thereby transversely sever the tube and transport the severed section thereof into position for engagement with the said stripping-member; and means for withdrawing the said axially-movable inner-cutter out of the portion of the tube within which it is normally located and after the completion of the tube-severing movement of the said second cutter-holder.

ANTHONY F. CIBS.
